(57) **CLAIM**

The ornamental design for a vibration actuator, as shown and described.

DESCRIPTION

FIG. 1 is a front view of a vibration actuator;
FIG. 2 is a rear view of the vibration actuator;
FIG. 3 is a top perspective view of the vibration actuator;
FIG. 4 is a bottom view of the vibration actuator;
FIG. 5 is a right side view of the vibration actuator;
FIG. 6 is a left side view of the vibration actuator;
FIG. 7 is a bottom perspective view of the vibration actuator;
FIG. 8 is a cross-section view of the vibration actuator taken along line 8-8 of FIG. 3; and,
FIG. 9 is a top plan view of the vibration actuator.
